UNITED STATES PATENT OFFICE.

WILLIAM LOUIS BESSOLO, OF McALESTER, OKLAHOMA.

WRENCH.

1,086,127.

Specification of Letters Patent.

Patented Feb. 3, 1914.

Application filed September 7, 1911, Serial No. 648,057. Renewed October 8, 1913. Serial No. 784,146.

To all whom it may concern:

Be it known that I, WILLIAM LOUIS BESSOLO, a citizen of the United States, and a resident of McAlester, in the county of 5 Pittsburg and State of Oklahoma, have invented a new and Improved Wrench, of which the following is a full, clear, and exact description.

My invention relates to wrenches, and has 10 for its object to provide a wrench having two jaw members pivoted together, one of the jaws being pivoted to the handle, the other jaw being connected to the handle by a link.

15 The wrench may be constructed at little expense, and with it it is possible to obtain a firm hold on a pipe or other similar material. As the wrench is constructed it is possible for a mechanic to make use of it 20 with one hand.

Other objects of the invention will appear in the following specification, in which the preferred form of my invention is described.

Similar reference characters refer to similar parts in all the views, in which—

Figure 1 is a side elevation of the invention; Fig. 2 is an end view of Fig. 1, and Fig. 3 is a transverse plan view of Fig. 1, on the line 3—3.

30 By referring to the drawings it will be seen that a handle 5 is provided, having an arm 6, a jaw member 7 being pivoted between two jaw members 8, the rear terminals 9 of the said jaw members 8 being pivoted to the handle 5. A link 10 is pivoted

35 to the arm 6 of the handle 5 at one end, the other end of the said link 10 being pivoted to the rear terminal 11 of the jaw 7. The

link 10 has several orifices 12, so that a pivot pin 13 may be disposed through any 40 one of these orifices to adjust the position of the jaw 7 relatively to the jaws 8 when the said jaws 8 are disposed substantially in alignment with the handle 5.

When using the wrench, the jaws 7 and 45 8 are disposed one at each side of a pipe or similar member 13^a and the handle 5 is moved to the right, which pulls the jaw 7 in the direction of the jaw 8, thereby clamping the pipe 13^a. 50

Having thus described my invention, I claim as new and desire to secure by Letters Patent:

In a wrench a handle having an arm with terminals spaced apart, the handle being provided with shoulders, one on each side, two jaw members disposed at opposite sides of the handle, and pivoted thereto, the jaw members having shoulders for engaging shoulders on the handle, a third jaw member disposed between the first-mentioned jaw members and pivoted thereto, and a link having terminals disposed between the terminals of the arm and pivoted thereto, the link extending between the 65 first-mentioned jaw members, with its other terminal forked at the other side of the first-mentioned jaw members, the third jaw member being pivoted between the forks.

In testimony whereof I have signed my 70 name to this specification in the presence of two subscribing witnesses.

WILLIAM LOUIS BESSOLO.
